DESIGN FOR A COMBINED LAMP AND ATTACHMENT CLAMP

George Popper, New York, N. Y.

Application April 25, 1940, Serial No. 91,943

Term of patent 7 years

To all whom it may concern:

Be it known that I, George Popper, a citizen of the United States, residing at 31 Union Square, New York, in the county of New York and State of New York, have invented a new, original, and ornamental Design for Combined Lamp and Attachment Clamp, of which the following is a specification, reference being had to the accompanying drawing, forming part thereof.

In the drawing:

Fig. 1 is a perspective view of the lamp showing my new design;

Fig. 2 is a side elevational view thereof;

Fig. 3 is a plan view thereof with the shade, bulb and upper portion of the socket omitted for better showing of the lower part.

The dominant features of my design reside in the portions represented in solid lines.

I claim:

The ornamental design for a combined lamp and attachment clamp, as shown and described.

GEORGE POPPER.
